UNITED STATES PATENT OFFICE.

FRANK A. FAHRENWALD, OF CLEVELAND HEIGHTS, OHIO.

ELECTRIC IRON.

Application filed February 6, 1922. Serial No. 534,344.

This invention relates to electric laundry irons and has for its objects the provision of a new, improved, and simplified device of this nature which shall be more cheaply and 5 easily constructed; more economical in current; less liable to burn out and more easily repaired in case of a burn-out than other devices. Another object of my invention is the provision in connection with such an iron 10 of a heating element made of a material having physical and chemical properties not heretofore united in any known substance and co-operating with the peculiar design of the iron to produce the result in view; while 15 further objects and advantages of the invention will become apparent as the description proceeds.

In the drawings accompanying and forming a part of this application I have illustrated certain physical forms in which my inventive idea can be embodied, but without intent to limit myself to the particular features of design or construction therein shown except as the same are specifically recited in 25 my claims.

Fig. 1 is a central longitudinal section through a complete iron containing my improvements; Fig. 2 is a top plan view of the base of the iron; Fig. 3 is a bottom plan 30 view of the insulating plate together with the resistance member; Figs. 4, 5, and 6 are views similar to Fig. 3 but showing different designs of winding, and Figs. 7, 8, 9, 10, and 35 11, are detail views illustrating different modes of affixing the resistance element to its supporting member.

Describing by reference characters the parts shown in the drawings 1 represents the base of an iron which is made in the usual or any desired shape, of cast iron or 40 other suitable alloy, its top being recessed as shown at 2 and the bottom of the recess preferably being formed with suitable ribs 3 arranged according to any desired pattern, 45 in order to increase the heat absorbing surface. To this base I secure in any suitable manner, as by the screw 4, a top comprising 50 a sheet-metal shell 5 shaped to fit snugly upon the base and having therein an insulating block 6 which depends into the recess 2 a suitable distance. The shell 5 is preferably lined with some insulating substance 7 such as asbestos, and I have further shown 55 a space 8 filled with some substance as mineral wool at the upper side of the block 6, the better to retain the heat where needed.

A suitable handle 9 is attached to the shell 5 by arms 10—10 in the usual or any suitable manner.

Secured to the lower face of the block 6 60 and projecting into close radiating relation with the base is a resistance element 12, preferably made in the form of a small helical coil of suitable wire, wound in any suitable or desired pattern to afford a uniform distribution of heat while at the same time affording sufficient length to produce the necessary resistance. Four different patterns or designs are shown in Figs. 3, 4, 5 and 6, and many others can be devised. The 65 terminals are attached in any desired way, one of the best being as shown in Fig. 1 wherein each end of the coil is attached to a bolt 13 of highly conducting material such as brass, whose upper end is secured by the 70 flexible lead 14 with a stud 15 fastened to the shell 5 by the insulated nuts 16 in such fashion as to receive the removable cord-terminal 17. The wire coil is held in place in any suitable manner, one mode being to loop it 75 back and forth around the headed studs 20 carried by the insulating block, these studs being either integral as shown in Figs. 7 and 8 or separable as shown in Fig. 9. In the last named case the body 6^b of the block 80 is formed with suitably located apertures 21 merging with counter-bores 22 at the upper surface, the apertures receiving the shanks 23 of the blocks 20^b which are held in place by suitable cement 24 introduced into the 85 counter-bores and interlocking with the grooves 25. Another mode of securing the resistance element is shown in Figs. 10 and 11 wherein the block 6^b is similarly formed with apertures 21 receiving the shanks of 90 suitable staples 26 which embrace the coil 12, the legs of the staples being outturned as shown at 27 and subsequently covered by an insulating layer 28. The body of the block 95 is preferably formed with a depending 100 flange 30 which fits inside the recess and tends to shield the walls from becoming overheated while directing the heat more particularly against the bottom of the recess. The thickness of the bottom must be so 105 chosen as to enable the iron to be quickly heated without at the same time becoming too quickly cooled and also to effect an even distribution of the heat, notwithstanding the necessary spacing of the convolutions of the 110 resistance element,

The essence of my invention consists in

mounting the resistance coil in heat-radiating relation to the base rather than in heat conducting relation therewith, said coil being supported upon a base which has insulating and reflecting qualities. It has long been attempted to produce a device of this character by embedding the resistance element in a suitable matrix or medium carried by the base which should convey the heat thereto while insulating the same electrically. Such a combination of properties in a single substance is almost unknown since most substances which are good conductors of heat are also good conductors of electricity, and the poor conductors of electricity are generally poor conductors of heat. In addition practically all the substances possessing the combined properties desired have a very brittle nature and possess a co-efficient of expansion which is far different from both the resistance element and from the iron base. Accordingly an element so constructed is very brittle subject to mechanical breakage, deteriorates rapidly upon repeated heating and cooling and generally gives rise to hot spots, which cause an early burning out of the element. However it is easy to find a substance which has both electrically-insulating, heat-insulating, and heat-reflecting properties, and any such substance will serve for the coil support in my improved iron. I prefer a good grade of porcelain owing to the fact that it possesses the necessary mechanical strength, electric resistance, and percentage of reflection. By reason of the fact that it overlies the coil its high heat-resistance becomes an advantage instead of a disadvantage in confining the heat effect to the bottom of the iron where it is needed. However it is well known that the transfer of heat by radiation varies with a higher power of the absolute temperature wherefore the iron works best when the element is maintained at a white heat, and owing to its exposure to the atmosphere and its suspension from above at spaced points, no substance has heretofore been known which was capable of producing such an element; owing to the fact that it must both withstand atmospheric oxidation and deformation due to sagging. Such a substance has been discovered by me in the form of certain alloys of chromium with iron, and one or more additional metals adjacent to iron in the periodic table of elements. The alloy used contains at least about 70 percent of iron, with about

20 percent of chromium, and a small proportion, say one to 3 percent of either or both of the materials manganese or titanium (or Zirconium). The specimen composition which I employ is:

	Per cent.
Iron	75
Chromium	22
Titanium	3 65

carbon and silicon being present as impurities to an amount of not above .5 percent each and preferably below about .4 percent each. Wires of this alloy drawn approximately to 28 gauge can be wound on a coil of pencil size supported as herein shown, and heated to incandescence for many hundreds of hours without exhibiting any observable sagging between their points of attachment. For the best effect it is desirable that the wires be shielded from below to the smallest possible extent thus permitting the maximum of radiation with the minimum number of supports.

It will be understood however that I do not limit myself to any details except as recited in the annexed claims.

Having thus described my invention what I claim is:

1. An electric iron comprising: a metallic base having a marginal upstanding flange defining a recess, upstanding ribs carried by the bottom of said recess, a cover portion having a flange fitting outside said upstanding flange, a lining of heat insulating material disposed in said cover portion, a block of non-conducting material disposed inwardly of said lining, an unconfined resistance element carried by said block spaced from but in radiating relation with the bottom of said recess, and means for securing together said base and said cover.

2. An electric iron comprising: a metallic base having a marginal upstanding flange defining a recess, upstanding ribs carried by the bottom of said recess, a heat insulated cover portion carrying a block of non-conducting material having a groove therein, an unconfined resistance element supported in said groove out of contact with but in radiating relation to said base, and means for securing together said base and said cover.

In testimony whereof, I hereunto affix my signature.

FRANK A. FAHRENWALD,
